UNITED STATES PATENT OFFICE.

JOHN W. JOHNSON, OF MORAVIA, NEW YORK.

FANNING-MILL.

SPECIFICATION forming part of Letters Patent No. 247,462, dated September 20, 1881.

Application filed February 19, 1881. (No model.)

To all whom it may concern:

Be it known that I, JOHN W. JOHNSON, a citizen of the United States, residing at Moravia, in the county of Cayuga and State of New York, have invented certain new and useful Improvements in Fanning-Mills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention relates to that class of fanning-mills for cleaning chaff from grain and sorting the same in which an upper shoe or screen-frame receives a transverse shaking motion while a lower screen receives a shaking movement in a longitudinal direction.

The chief object of the invention is to provide a lighter and stronger shaking-screen shoe than has heretofore been known, also to provide means whereby an accelerated motion can be imparted to the various screens from a fan-shaft driven at the ordinary rate of speed. I attain these objects by the construction and combination of parts hereinafter described and claimed.

In the drawings, Figure 1 is a side elevation of my fanning-mill, exhibiting the double-crank wheel and other devices for imparting motion to the screens. Fig. 2 is a longitudinal sectional view, showing the interior construction and arrangement of parts. Fig. 3 is a detached view of my skeleton shaking-shoe.

The letter A designates the casing of the mill, and B is the feed-hopper at the top thereof. One end of the casing is closed by the customary hood inclosing the air or blast fan, and the other end is open for permitting the escape of the chaff and light stuff blown out by the action of the air-blast. The fan-shaft C is journaled in the casing, and has a double set of fan blades or wings, D, arranged thereon. The arms F of these blades are secured to the shaft by means of disks or collars, E, which are provided with flanges e, forming seats for the arms F. The latter are bolted or otherwise secured to the flanged collars. The construction shown presents a double-fan wheel, by means of which a stronger and more even

blast is produced than with an ordinary single fan. While I prefer to use a double fan, I may, in certain instances, resort to a single fan which is composed of curved vanes or blades attached to the outer ends of arms secured to the fan-shaft in the manner already described. 55

The fan-shaft is driven by means of the ordinary spur or other gearing and carries a double sliding crank wheel, G, which serves 60 to impart a quick or accelerated movement to the various screen-fans. The crank-wheel has the intersecting face-slots, in which move two blocks, g, carried by the longitudinal shake-rod H. The rear end of this rod is connected 65 with a horizontal bell-crank lever, I, which is pivoted in suitable brackets on the mill-casing, and is connected with the transversely shaking or reciprocating screen-shoe J by means of the link or hook K, passing through a slot in said 70 casing. The shoe J is made of a skeleton form, and is otherwise so constructed that it combines lightness with strength, whereby the mill runs easier and stands firmer upon the floor when in operation than ordinary mills 75 provided with heavier shoes having solid side walls. A shoe made wholly from boards is also liable to warp or split or bind against the side walls of the mill-casing, whereas the skele-ton-shoe employed by me possesses no such 80 disadvantages. The shoe J is made with the rear pair of vertical standards or plates, L, the longitudinal top rails or wooden bars, M, and the front pair of vertical standards or plates, N. The upper ends of all these bars are con- 85 structed with flanges for receiving and sup- porting the top rails, M, and their lower ends are provided with sockets or caps O, which receive the ends of the wooden connecting-bars P. The rear standards are made shorter 90 than those at the front end of the shoe, and the two pairs of standards are at right angles to each other—that is, the rear standards pre- 95 sent their edges to the rear of the mill, while the front standards present their faces or sides. 95

The inner edges of the front standards, N, are provided with notches n, two or more in each standard, which receive the side bars of the screen-frame Q. The rear cross-bar of said screen-frame rests upon a transverse rod, 100 R, which is fitted into notches l, made in the outer edges of the rear standards. The rod R

may have a loop at one end, which engages with a hooked projection of one standard, and have its other end screw-threaded for the reception of a retaining-nut. The object of the 5 notches in the front standards is to enable the screen-frame to be raised and lowered to give it a greater or less degree of inclination. The customary board, S, of the shoe conducts the grain from the hopper upon the sieve, where 10 it is subjected to the action of the air-blast. The front and rear standards are extended above the top rails of the shoe, or suitable flanges or ears of said standards may rise above said rails for forming boxes or bearings for small 15 rollers T. These rollers are generally grooved and arranged in pairs, and run upon transverse rods or rails U, fitted into the side walls of the casing. It will be observed that these rods and rollers support the shoe and enable it to receive 20 a lateral shaking movement in the manner and for the purpose already stated.

The skeleton-shoe is provided with adjustable side-boards D², which extend the whole length of the shoe and prevent the grain from falling 25 off from the sides thereof. These side-boards or false sides are carried by vertical arms D³, which are slotted at their upper ends, and are adjustably secured to the top rails of the shoe by means of screws passed through the slots of 30 said arms. This construction of the side-boards permits the screen to be adjusted in the manner already stated. As represented in the present instance, the lower sieve-frame, V, has a longitudinal reciprocating movement imparted 35 thereto by means of a transverse rock-shaft, W, and fingers w, secured thereto. This rock-shaft may be arranged above or below the lower sieve; but in either case the fingers thereof engage with or enter notches or grooves made in 40 the side bars of the sieve-frame. A rocking motion is given to the rock-shaft through the medium of a connecting-rod, X, connected with the main shake-rod and a crank-arm on the outer end of the rock-shaft.

45 The means above described suffice to impart the requisite longitudinal movement to the lower sieve-frame, and in addition thereto said sieve receives a vertical jarring motion for preventing clogging thereof. This is done by the 50 corrugated rollers Y, attached to the sides of

the casing, on which the side bars of the sieve roll.

Instead of operating the lower sieve in the manner above stated, I may operate it by connecting it directly with the upper laterally-shaking shoe, so as to have all the operating devices inside the casing. The means for effecting this operation comprise a rod or link on the rear transverse bar of the upper shoe, a bell-crank lever pivoted to a stationary cross-bar 60 fitted in the casing below said transverse bar of the shoe, and a rod connected with the bell-crank lever and the lower sieve.

It will be obvious that by connecting the lower screen with the upper shoe by the means 65 described said screen receives the requisite longitudinal shaking motion.

The discharge of grain from the feed-hopper is regulated by means of a movable bottom, Z, which can be adjusted so as to enlarge or 70 diminish the size of the discharge throat or opening. A transverse lever, Z'', journaled in one side wall of the casing, passes under the board Z and is secured thereto, and projects through an inclined slot, z', in the other side 75 wall of the casing. Said lever serves as a rest for the hopper-bottom, and is also the medium for adjusting the same.

Having thus described my invention, what I claim as new, and desire to secure by Letters 80 Patent, is—

1. A fanning-mill shoe constructed of front standards for receiving and adjustably supporting a sieve-frame, notched rear standards having a transverse sieve-supporting rod fitted 85 therein, upper longitudinal rails to which said standards are rigidly secured, and transverse bars rigidly connecting the latter at their lower ends in pairs, substantially as and for the purpose set forth.

2. A fanning-mill shoe having a vertically-adjustable sieve and side-boards made vertically movable independently of said sieve, as and for the purpose set forth.

In testimony whereof I affix my signature in 95 presence of two witnesses.

JOHN W. JOHNSON.
